UNITED STATES PATENT OFFICE

WILLIAM CREPEAU, OF SCOTIA, NEW YORK.

WATER-CYCLE.

No. 919,134.

Specification of Letters Patent.

Patented April 20, 1909.

Application filed September 26, 1907. Serial No. 394,636.

To all whom it may concern:

Be it known that I, WILLIAM CREPEAU, a citizen of the United States, residing at Scotia, county of Schenectady, and State of New York, have invented certain new and useful Improvements in Water-Cycles, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a central longitudinal section of a boat, showing the operating mechanisms in elevation. Fig. 2 is a side elevation of the gear-inclosing case and the gear-shafts erected in the bottom of the boat, the other parts being broken away for convenience of illustration. Fig. 3 is a cross-section of the gear-inclosing case taken 25 on the broken line 3—3 in Fig 2. Fig. 4 is a vertical cross-section taken on the broken line 4—4 in Fig. 2. Fig. 5 is a view similar to that shown in Fig. 2, with a portion of the case removed, showing the inclosed gears 30 and the base shown partly in section. Fig. 6 is a view in side elevation of a portion of the steering mechanism. Fig. 7 is an end elevation of the part shown in Fig. 6, seen in the direction of the arrow. The fragmentary 35 figures, 2 to 7 both inclusive, are made upon an enlarged scale.

The boat-body, 1, is shown for convenience of illustration made in one piece of material provided with the floor, 2, from 40 which is erected a cycle-frame, 3, similar to the ordinary tandem bicycle-frame. This frame is provided with bearings for the pedal-shafts, 4 and 5, upon which are secured the pedals, 6 and 7, respectively, the upper portion 45 of the frame being provided with two seats, 8 and 9, and with the steering bar 10. When two sets of pedals and two seats are employed, the pedal-shafts are each provided with a sprocket-wheel, 12, and such 50 wheels are connected by a sprocket-chain 13.

The propeller screw, 20, is fixed upon a shaft, 21, rotary in suitable bearings, 22, in the rear end of the boat-body, which bearings are provided with a stuffing-box, 23, which 55 may be made in any known manner. The

inner end of the shaft, 21, is rotary in bearings, 24, secured to the bottom of the boat, as shown in Fig. 1.

The pedal-shaft, 5, is provided with a beveled gear-wheel, 30, fixed thereon, as by the 60 key 31. This gear-wheel meshes with the beveled pinion, 32, fixed upon the shaft, 33, which shaft is connected with the propeller-shaft, 21, by means of a link, 34, having a universal joint-connection at one end with 65 the gear-shaft, and at its other end with the propeller-shaft. The universal joints may be of any known form of construction, but are shown in the well known form of two yokes pivoted together, as by pivots 35 and 36. 70

The gear connections, 30 and 32, are inclosed within a case, 40, shown in section in Fig. 3. The case comprises the body-section, 41, and the cover-section, 42, secured thereto by screws 43. The two sections of 75 the case provide the bearings for the pedal-shaft, 5, passing therethrough. The gear 30, is inclosed between the two sections of the case, as shown, and the bearing for the shaft, 33, is located between the section, 41, 80 and the bearing-box section, 44, secured to the case-section. The two case-sections and box-section are so fastened together as to form a tight chamber for the gearing; and, by inserting an oil cup, 46, having an exteriorly screw-threaded stem, 47, in the rim of the boat-section of the case, and which is provided with a screw-threaded aperture adapted to receive the screw-threaded stem, oil can 85 be supplied in the ordinary manner of using 90 oil-feeding cups to keep the gear-inclosed chamber supplied with oil, which serves to lubricate the gearing as well as the bearings of the gear-shafts. The shaft, 33, is provided with a balance-wheel 49. By connecting the 95 driving-shaft, 33, with the propeller-shaft, 21, by universal joint-connection, as shown, I am able to erect the frame which supports the pedal-shafts and driving gear upon the bottom of the boat, while placing the propeller-shaft on a much lower level, necessary to wholly submerge the propeller beneath the water-line indicated by the lines 50. 100

As a means for steering the boat, I have provided the rudder, 51, projecting from the 105 rudder-post, 52, which is capable of a rocking movement in the bearing 53. The rudder-post is provided with a lever, 54, and operating cables, 55, extending along the respective sides of the boat in the usual well known 110

manner, which cables are wound upon a windlass, 56, so that a rotary movement of the windlass in one direction will steer the boat to the right, and in the opposite direction will steer the boat to the left.

As a means for communicating rotary movements to the windlass, I provide two sets of mechanisms, one set consisting of a hand-wheel, 57, fixed upon the shaft, 58, 10 rotary in a bearing, 59, and secured by a universal joint, 60, to the windlass or drum. This wheel, 57, is accessible to an operator standing at the bow of the boat. The other set of steering mechanism comprises the 15 handle-bar, 10, accessible from seat, 8, such handle-bar being secured to the shaft, 61, capable of rocking movements in the bearing, 62, secured to the frame 3. The lower end of the rock-shaft, 61, is connected to a 20 horizontal rock-shaft, 63, by means of a link, 64, connected at one end to the shaft, 61, by means of a universal-joint, 65, and at its opposite end to the shaft, 63, by means of a universal-joint 66. The forward end of 25 the rock-shaft, 63, is provided with the gear segment, 70, fixed thereon and adapted to mesh with the pinion, 71, fixed upon the shaft 72, rotary in bearings 73. Fixed upon the other end of the shaft, 72, is the sprocket- 30 wheel, 74, connected by a sprocket-chain, 75, with the sprocket-wheel, 76, fixed upon the journal, 77, of the windlass 56. I am thus able to provide duplicate steering mechanisms, one set of steering mechanism being 35 accessible from the forward pedal seat, from which seat the operator of one set of pedals can steer the boat, and the other set of steering mechanism being accessible to the helmsman standing in the bow of the boat, 40 the universal joint-connection between the upright rock-shaft, 61, and the horizontal rock-shaft, 63, permitting the connections between the steering handle-bar and the windlass to be carried along the bottom of the 45 boat, where it will not interfere with the convenience of passengers on the boat.

By having the pedal-shafts and driving-shaft located at a comparatively high level, room is afforded for the revolution of the 50 pedals above the floor of the boat, and by having the driving-shaft at the same level and extended in a horizontal plane, room is afforded for securing the drive-wheel to such shaft, and it is possible to rotate the 55 wheel in a vertical plane without the gyro-

scopic effect which would be produced if the shaft was placed in an inclined position, which effect would produce greater wear upon the bearings. And by having the propeller-shaft parallel with the driving-shaft, but at 60 a lower level, the screw will be wholly submerged in the water and the force of its thrust will be directly in line with the travel of the boat.

What I claim as new and desire to secure 65 by Letters Patent is—

1. In a water-cycle, the combination with a boat-body; of a propeller-shaft rotary in suitable bearings and projecting through one end of the boat-body at a level below the 70 water-line; a pedal actuated driving-shaft located at a level above the level of the propeller-shaft and approximately parallel therewith; an inclined link connected at its upper end by a universal-joint with the driving-shaft, and connected at its lower end with the propeller-shaft by a universal-joint; and a fly-wheel fixed on the driving-shaft. 75

2. In a water-cycle, the combination with a boat-body; and the propeller-shaft through 80 one end of the body; of a pedal-shaft; a driving-shaft; a connection between the driving-shaft and propeller-shaft; gear-connections between the pedal-shaft and driving-shaft; a gear-inclosing case comprising a body section, 85 a cover section and a bearing-box section, the three sections being detachably secured together to form a tightly-inclosing case, the body and cover sections being provided with bearings for the pedal-shaft, and the box section and the body section being provided with bearings for the driving-shaft; and means for supplying the case-chamber with oil. 90

3. In a water-cycle, the combination with 95 a pedal-operated propeller and a rudder; of a frame erected within the boat provided with bearings for the pedal-shaft; a seat mounted upon the frame; duplicate steering mechanisms comprising a handle-bar in front of the 100 seat and the steering wheel in the bow of the boat; and operating connections between such bar and wheel and the rudder.

In testimony whereof, I have hereunto set my hand this 21st day of September, 1907. 105

WM. CREPEAU.
